UNITED STATES PATENT OFFICE.

WILLIAM L. HARRIS, OF PETERSBURG, VIRGINIA.

PEANUT-PLANTER.

1,063,028.

Specification of Letters Patent.

Patented May 27, 1913.

Original application filed September 1, 1911, Serial No. 647,270. Divided and this application filed December 27, 1911. Serial No. 668,166.

To all whom it may concern:

Be it known that I, WILLIAM L. HARRIS, citizen of the United States, residing at Petersburg, in the county of Dinwiddie and 5 State of Virginia, have invented certain new and useful Improvements in Peanut-Planters, of which the following is a specification.

This invention has relation to peanut 10 planters, and has for its object to provide a nut selecting and dropping mechanism of peculiar arrangement designed to select individual nuts from a quantity carried in a hopper and convey the same to a boot 15 through which the nuts are dropped successively into a furrow opened in the soil.

The subject matter of the present invention is divided from my copending application for patent for peanut planter, filed 20 September 1, 1911, Serial No. 647,270.

For a full understanding of the invention reference is to be had to the following description and accompanying drawing, in which:

25 Figure 1 is a sectional view of a hopper with the dropping mechanism applied, showing parts thereof in section; Fig. 2 is a perspective view of a shield used in the dropping mechanism; Fig. 3 is a perspective view of a portion of the rim of a wheel used in the dropping mechanism; and Fig. 4 is a perspective view of a casting used in the dropping mechanism.

Corresponding and like parts are referred 35 to in the following description and indicated in all the views of the accompanying drawing by the same reference characters.

The seed selecting and dropping mechanism includes a hopper 36 which may be positioned in any suitable manner upon a planter frame indicated in general in the drawing but not shown in detail. The hopper 36 is provided at its bottom and at its rear side with a slot 37. A wheel 38 is 40 journaled for rotation at the rear side of the hopper 36 and the forward portion of the said wheel projects through the slot 37. The wheel 38 is fixed upon a shaft 39 and 45 any suitable means (not shown) may be provided for rotating the said shaft. The wheel 38 is provided at its periphery with a series of lugs 41 and each lug 41 is provided at each end with recesses 42 and 43. The recesses 42 are of greater diameter than 55 the recesses 43 and the peripheral portions

of the wheel 38 between the lugs 41 are approximately V-shaped in transverse section, as at 44. The ridges of the portions 44 of the wheel are in alignment with the inner sides of the recesses 42 and 43. Consequently the said ridges are not in true arcs concentric with the center of the wheel but are eccentrically positioned, for the reason that the recesses 42 and 43 are of different diameters.

A boot 45 is carried by the frame of the planter and the wheel 38 is located directly above the upper end of the boot. A disk 46 is journaled at the lower portion of the boot 45. A shield 47 is provided with side portions which normally lie at the opposite sides of the upper forward portion of the wheel 38 and at the side edges of the slot 37 in the hopper 36. This shield is adapted to prevent the nuts or seed from coming in contact with the spokes of the wheel 38. At its upper portion the shield 47 is provided with a hood section 48 which extends around the upper rear portion of the wheel 38 and which is hingedly connected at its rear end with a hood section 49 which in turn is rigidly supported upon the hopper 36. The discharge end of the hood section 48 is located above the receiving end of the boot 45.

A casting 50 is attached to the bottom of the hopper 36 at the forward end of the slot 37. This casting is provided at its rear portion with a groove 51 which receives the lower forward lugs 41 upon the periphery of the wheel 38. The casting 50 is located between the bottom of the hopper 36 and the upper forward edge of the boot 45.

The operation of the device is as follows: The disk 46 makes an incision in the soil. 95 At the same time the shaft 39 and the wheel 38 are set in motion so that the upper portion of the said wheel rotates in a rearward direction. As the lugs 41 move upward from the casting 50 the seed with which the hopper 36 is supplied will lodge in the uppermost recesses at the ends of the lugs 41 and are carried up under the hood section 48, thence down through the hood section 49 and are dropped into the boot 45. As each lug 41 moves above or clears the upper portion of the casting 50 a nut may fall down into the groove 51 of the said casting and thus it is positioned so that it may readily enter the recess of the next succeeding lug 100 105 110

41. By providing the lugs 41 at their opposite ends with recesses of different diameters the said wheel 38 may be reversed or turned and positioned upon the shaft 39 so that large or small nuts may be planted. As the lugs 41 move in an upward direction through the casting 50 the uppermost recesses therein receive the seed and carry them up as the said lugs pass through the 10 hood and the recesses which receive the seed are turned into inverted positions, the seed passes from the lug by which it is elevated to the preceding lug and is carried down and deposited in the boot 45 without danger of 15 bruising or crushing.

Having thus described the invention what is claimed as new is:

1. A seed selecting and dropping mechanism including a hopper having a slot 20 formed in its bottom and side, a rotatably mounted seed wheel projecting into the hopper through the slot, a boot positioned beneath the wheel, a hood section supported by the hopper and extending about a portion 25 of the wheel to maintain the seed in place, and a second hood section hinged by one end to the first and bearing about the upper portion of the seed wheel, said second

hood section being provided at its free end with downwardly extending shields having 30 angularly disposed edges adapted to seat against the bottom and side of the hopper when the shield is in lowered position to prevent the seed in the hopper from coming in contact with the wheel spokes. 35

2. A seed selecting and dropping mechanism including a hopper provided with a slot, a seed wheel rotatably mounted and extending through the slot, and a guard for said seed wheel carried by the hopper, said guard including a lower section secured to the outer face of the hopper and a second section hinged to the upper end of the lower section and provided at its free end with downwardly extending shields which bear 40 against opposite sides of the wheel and which seat against the inner walls of the hopper to take the strain off from the securing means of the first section. 45

In testimony whereof I affix my signature 50 in presence of two witnesses.

WILLIAM L. HARRIS. [L.S.]
